UNITED STATES PATENT OFFICE.

JOHN P. WALTER, OF ALLENTEWON, PENNSYLVANIA.

SHOVEL.

Application filed November 10, 1926. Serial No. 147,482.

This invention relates to a power shovel which is mainly designed for handling coal in mines but which, of course, can be used for handling other material, the general object 5 of the invention being to so form the device that it can be used in restricted areas and in places where the head room is limited.

Another object of the invention is to provide means whereby the shovel will cut material from a bank or pile and deliver it to a transfer plate which will in turn deliver the material to a conveyor, with means on the apparatus for operating the shovel, the transfer plate and the conveyor as well as to cause the 15 entire apparatus to travel along a surface.

A further object of the invention is to provide a cutting device at one side of the shovel for cutting a straight wall at this side of the apparatus.

20 Another object of the invention is to provide a rail with double flanged wheels on the apparatus for engaging the rail to keep the apparatus traveling in a straight line.

This invention also consists in certain other 25 features of construction and in the combination and arrangement of the several parts, to be hereinafter fully described, illustrated in the accompanying drawings and specifically pointed out in the appended claims.

30 In describing my invention in detail, reference will be had to the accompanying drawings wherein like characters denote like or corresponding parts throughout the several views, and in which:—

35 Figure 1 is a plan view of the device.
Figure 2 is an elevation thereof.

Figure 3 is a side view of the opposite side from that shown in Figure 2.

40 Figure 4 is a front view.
Figure 5 is a section on line 5—5 of Figure 1.

45 Figures 6, 7 and 8 are diagrammatic views showing the various positions of the rotary shovel and transfer plate during the operation of the device.

In these drawings, 1 indicates the frame of the machine which at one side thereof is provided with the double flanged wheels 2 which are designed to run on the single rail track 3, 50 the rest of the machine being so formed that it can slide over the surface upon which it is traveling. The double flanged wheels, engaging the single rail, will cause the machine to travel in a straight line and prevent it from 55 slewing around. Of course, both sides of the machine may be provided with wheels, if de-

sired, and the wheels may be so constructed that the device can travel on a track or they may be so made that the device need not be used with a track.

60 A rotary shovel 4 is arranged at the front of the machine and the said shovel comprises a hollow shaft 5 journaled in the frame and having a disk 6 at each end thereof and also having secured thereto the end spiders 7, 65 which are arranged adjacent the disk and the central spider 8. A pair of plates 9 is secured to the spiders, the plates being secured to opposite sides of the spiders and extending in opposite directions with their outer portions 70 curved to form the scoops 10, these scoop portions being provided with the teeth 11. Thus it will be seen that as the shovel rotates, the scoops will engage material in front of the apparatus and separate some of it from the pile 75 or bank and carry it upwardly and then toss it to the rear of the shovel where it will fall upon a tilting or transfer plate 12 which has its rear end fastened to a shaft 13 which is journaled in the frame. This plate, as it is tilted upwardly, will discharge the material thereon upon a transversely extending conveyor 14 which will deliver the material to a point at one side of the apparatus. This conveyor includes the endless belt 15 and the rollers 16 80 and 16' over which the belt passes, the journals for the pintles of the shaft 16 being adjustable to take up slack in the belt, as shown at 17.

85 A shaft 18 is rotatably mounted in the hollow shaft 5 of the shovel and a cutter wheel 19 is connected to the right hand end of the said shaft 18, this wheel having the bits 20 on its periphery. A plow or mold board 21 is arranged at the opposite end of the rotary shovel for throwing material in front of the rotary 90 shovel, this mold board being carried by a forwardly extending part 1' of the frame 1, which also carries the front wheel 2.

95 A motor 22 is supported on the frame, this motor being shown as an electric one but it will, of course, be understood that it can be of any desired type. The shaft 23 of the motor is connected by the worm gearing 24 with a shaft 25 journaled in the frame 1 and this shaft 25 is connected by the beveled gears 26 with a shaft 27 which has fastened thereto the sprockets 28 and 29. A chain 30 passes over the sprocket 28 and over a sprocket 31 which is connected with the hollow shaft 5 of the rotary shovel so that the 100 shovel is rotated when the shaft 27 is rotated from the motor and a chain 32 passes over the 105

110

sprocket 29 and over a sprocket 33 which is connected with the shaft 18 of the cutting wheel 19.

A shaft 34 is connected with the shaft 27 by the gears 35 and the said shaft 34 has a crank 36 at one end thereof which is connected by the connecting rod 37 with a crank 38 on the shaft 13 of the transfer plate so that said plate is tilted by the rocking movement of the shaft 13 through the rotary movement of the shaft 34 which is transmitted to the shaft 13 through the cranks and connecting rod. A shaft 39 is journaled in the apparatus and has a gear 40 thereon which meshes with the gear 35 on the shaft 34 and the said shaft 39 is connected to a pintle of the roller 16' of the conveying means by means of the beveled gears 41.

A clutch 42 is placed on the shaft 27 for connecting its gear 26 with the said shaft and the said clutch is operated from the rear of the machine through the shaft 43 and the handle 44. Thus the rotary shovel, the cutter wheel, the transfer plate and the conveyor can be disconnected from the motor by moving the clutch to inoperative position, but when the clutch is in operative position, the rotary shovel and the cutter disk will be rotated, the transfer plate tilted and the conveyor operated from the motor.

It will be seen that the cutter disk is entirely independent of the rotary shovel so that it can be driven at a different speed than that of the shovel, the speed of the shovel and of the cutter disk being regulated by the sizes of the sprockets used for driving these parts. It will also be understood that where two scoops are used on the shovel, the material will be delivered to the transfer plate twice during each revolution of the shovel, so that it will be necessary to operate the plate twice for each revolution of the shovel so that it will discharge the material received from one scoop upon the conveyor and then return to normal position to receive the material from the second scoop and then discharge this and return to normal position to receive the material from the first scoop.

Any desired means may be used for propelling the apparatus. The drawings show a large sprocket 45 and a small sprocket 46 on a shaft 47 which is driven from the shaft 25 through the worm gearing 48, clutch means 49 being provided for connecting the sprockets with the shaft. A chain 50 is adapted to be placed in engagement with either sprocket 45 or 46 according to the speed at which the apparatus is to be moved, it being seen that the sprocket 46 is smaller than the sprocket 45 so that the apparatus would be moved at a slower speed if the chain is placed in the sprocket 46 instead of the sprocket 45. The chain passes over the idle sprockets 51 or 52 and has its ends connected with anchor posts 65 so that the chain is held stationary and as the

shaft 47 rotates, it will rotate the sprocket and thus cause the apparatus to move along the chain in one direction or the other according to the direction of rotation of the motor.

If desired, a drum can be substituted for the sprockets and a cable substituted for the chain and other means for propelling the apparatus.

A drum 53 is adapted to be connected with the shaft 47 by the clutch 54 and this drum 75 can be used for receiving a cable for handling props and other material and it can also be used as a power cable drum.

From the foregoing, it will be seen that after the chain or cable has been anchored 80 ahead and in the rear of the apparatus and the motor starts up and the clutches 42 and 49 moved to operative position, the machine will travel forwardly on the rail and into the material to be loaded. As the shovel 85 rotates, it will pick up the material and deposit it upon the tilting plate which operates twice as fast as the shovel, if the shovel is provided with two scoops and the said plate will deposit the material upon the conveyor 90 which conveys it to one side of the apparatus where it can be deposited upon cars or other vehicles or it can be deposited upon a second conveyor which will carry it to the rear of the machine. The shovel can be provided with but one scoop, if desired. Figures 95 5, 7 and 8 show the manner in which the shovel and transfer plate operate to carry the material to the conveyor without the plate interfering with the movement of the 100 shovel.

The cutter disk will operate to dress one face of the wall or pile of material being handled by the apparatus, so that this cutter disk acts to leave a straight vertical wall at 105 the right hand side of the device. The plow at the left hand side acts to throw the material in front of the shovel.

This apparatus is mainly designed for use in coal mines where head room is limited. 110 As is well known, the usual practice in such mines is to make an undercut in the wall of the coal vein, after which holes are drilled near the roof of the vein to receive the powder so that the coal above the undercut is shot 115 down. This usually leaves an arch which starts at the inner end of the undercut and extends to the roof of the vein, leaving a mass of material overhanging the undercut. This must be dressed straight before another cut 120 can be made. At this point the machine is brought into operation, the rotary shovel acting to tear down the overhanging mass of material, with the rotary disk cutter leaving a straight wall or face at the right hand side 125 of the vein.

What I claim is:—

1. A power shovel comprising a frame, a rotary shovel at the front end of the frame, a conveyor, a rocking plate for transferring 130

the material from the shovel to the conveyor and a power device for operating said conveyor and the rocking plate, said power device driving a shaft connected by one train of gearing to the rotary cutter and by another train to the rocking plate.

2. A power shovel comprising a frame, a rotary shovel at the front end of the frame, a conveyor, a rocking plate for transferring the material from the shovel to the conveyor, a cutter disk at one side of the frame for leaving a straight wall of material at this side of the apparatus and a power device for operating the conveyor, the rocking plate and the cutter disk, said power device driving a shaft connected by one train of gearing to the rotary cutter and by another train to the rocking plate.

3. A power shovel comprising a frame, a rotary shovel at the front thereof, a conveyor, a tiltable transfer plate for receiving the material from the shovel and delivering it to the conveyor, a vertically arranged cutter disk at one side of the frame, and power means for operating said parts, such means including means for rotating the cutter disk at a different speed from that of the rotary shovel.

4. A power shovel comprising a frame, a rotary shovel at the front thereof, a conveyor, a tiltable transfer plate for receiving the material from the shovel and delivering it to the conveyor, a vertically arranged cutter disk at one side of the frame, power means for operating said parts, such means including means for rotating the cutter disk at a different speed from that of the rotary shovel and means for propelling the apparatus from the power means.

5. A power shovel comprising a frame, a rotary shovel at the front thereof, a conveyor, a tiltable transfer plate for receiving the material from the shovel and delivering it to the conveyor, a vertically arranged cutter disk at one side of the frame, power means for operating said parts, such means including means for rotating the cutter disk at a

different speed from that of the rotary shovel, means for propelling the apparatus from the power means, a single rail track and wheels at one side of the frame engaging the track.

6. A power shovel comprising a frame, a rotary shovel at the front end thereof, said shovel comprising a hollow shaft and scoops thereon, a shaft journaled in the hollow shaft and having its ends projecting therefrom, a cutter disk connected with one projecting end, a tiltable transfer plate for receiving material from the rotary shovel, a conveyor for receiving material from the transfer plate, a power device on the frame and means for communicating the movement thereof to the various parts, such means including means for driving the hollow shaft at a different speed from the shaft which carries the cutter disk.

7. A power shovel comprising a frame, a rotary shovel at the front thereof, said shovel including a hollow shaft and scoops connected with the shaft, a second shaft passing through the hollow shaft, a cutter disk connected with one end of the said second shaft, a tiltable transfer plate, a rock shaft carrying the same, a conveyor, said plate receiving the material from the rotary shovel and depositing it upon the conveyor, a motor, a shaft driven from the same, a sprocket and chain for connecting the said last mentioned shaft with the hollow shaft, a chain and sprockets connecting the driven shaft to the shaft which carries the cutter disk, a crank shaft, gears connecting the same with the driven shaft, a crank on the rock shaft, a connecting bar connecting said crank with the crank of the crank shaft, means for operating the conveyor from the crank shaft and a plow at that side of the frame which is opposite to that on which the cutter disk is arranged for throwing material in front of the rotary shovel and means for propelling the apparatus from the motor.

In testimony whereof I affix my signature.
JOHN P. WALTER.
